EASTMAN A. WEAVER, OF WINCHESTER, MASSACHUSETTS, ASSIGNOR, BY MESNE ASSIGNMENTS, TO STATOR REFRIGERATION, INC., A CORPORATION OF DELAWARE

FLUID PUMPING

Application filed July 20, 1929. Serial No. 379,844.

This invention relates to an improved apparatus and method for feeding fluid from a region of low pressure to a warmer region at higher pressure concomitantly with the evaporation of the fluid.

The present invention is particularly designed to provide fluid feed means which is adapted to a wide variety of use and which effects the automatic circulation of fluid from a low pressure region to a region at a higher temperature and pressure without the necessity of moving parts, auxiliary liquid circuits to pump the fluid, or the like. Accordingly means of this character for inducing fluid flow is particularly useful in apparatus which should require a minimum of expert mechanical attention, replacement of parts, etc. For example, in the field of household refrigeration it is highly desirable to avoid the use of mechanical pumps or the like with the accompanying vibration, noise, wear, and possible mechanical failure, and in apparatus of this character it is desirable to return a circulating fluid to the boiler, which preferably is maintained at a comparatively high pressure. The present invention provides means which may be advantageously used in conjunction with a refrigerating system of the absorption type to return the strong solution of refrigerant and absorbent liquids to the generator against a comparatively high pressure in the latter. Fluid feed apparatus of this character may also be advantageously used in conjunction with refrigerating apparatus of the character disclosed in my copending application Serial No. 733,699, filed August 23, 1924, patented June 3, 1930, #1,761,551 permitting such a system to operate with greater pressure differentials and accordingly higher efficiency and/or permitting the system to be more compact than otherwise possible.

While I have particularly referred to the advantages and utility of the fluid feeding apparatus in conjunction with refrigerating systems, it is obvious that this is but a typical application of the invention and that the same may be employed in a wide variety of environments where it is desired to direct fluid from a low pressure region to a high

pressure region where it is vaporized. In order to permit the automatic pumping of fluid in this manner I preferably utilize a wall of porous material between the regions at different pressures, supplying the fluid in its liquid phase to the low pressure side of the wall which is provided with numerous capillary passages that are adapted to feed the fluid to the high pressure portion thereof. Preferably the circulating fluid and the porous material are so chosen that the fluid in its liquid phase will readily wet the material, having a suitable surface attraction in relation to the chosen capillary material so that its surface forms a very small angle of contact with the walls of the capillary passages, the diameter of which should be inversely proportioned to the pressure against which it is desired to pump. When the circulating fluid and capillary material are thus chosen, the liquid will continue to flow toward the high pressure ends of the capillary passages where it is vaporized, despite a considerable difference between the pressures at opposite ends of the passages; for example, fluid may be circulated against pressure differences of well above one atmosphere. The employment of a liquid having a very small angle of contact with the capillary passage permits the evaporation of the same due to the heat supplied at the high pressure side of the porous wall and the automatic replenishment of the evaporated liquid from the low pressure side of the wall so that the concave surface of the minute liquid column does not retreat under the higher pressure to which it is subjected; in other words, as the pressure increases due to the evaporation of the liquid in response to heat, the surface of the liquid at the end of a capillary passage becomes stretched while the advanced edges thereof in contact with the wall retain substantially the same position.

In order to permit the effective heating of the liquid in order to cause rapid evaporation of the same, I preferably locate a heat conductive non-volatile material of a type which will not wet the walls of the capillary passages in contact with the high pressure side of the porous wall. Thus, for example,

unglazed porcelain or earthenware may be employed in conjunction with many circulating liquids, and mercury or lead may be employed as the heat conductive, non-volatile liquid in contact with the high pressure side of the wall, it being understood that the vaporized circulating liquid bubbles through this liquid and is vented through a suitable outlet duct.

10 In the preferred practical application of my invention, I supply the circulating liquid to a suitable chamber within which a boiler is located, one end of the chamber preferably forming one end of the boiler wall and the remainder of the boiler being formed by a cup of porous material with its edges held in pressure-tight relation with the common wall of the boiler and chamber. Preferably heat is supplied to the interior of the boiler 15 so that the heating factor is not in direct heat transfer relation to the contents of the chamber which surround the boiler. Accordingly the incoming liquid may remain at a temperature at which evaporation of the same does not readily occur until it passes through the 20 wall of the porous cup. The latter is arranged to provide an ample area, i.e. a large number of capillary passages, so that an adequate amount of fluid may flow through the 25 same, the thickness of the cup being so determined in relation to its area and the capillary characteristics thereof as to permit the flow of the proper amount of fluid. Furthermore, since the material of the cup is porous, it 30 forms a rather poor heat conductor and thus aids the maintenance of the lower temperature of the liquid upon its low pressure side. Furthermore, the flow of the liquid inwardly tends to counteract the flow of the heat outwardly. Preferably, if the heating factor 35 is of the combustion type, the flue for burned gases is also connected to a portion of the boiler that is remote from the liquid surrounding the same and similarly the vapor generated by the boiler preferably passes out 40 through a duct which is not in direct heat transfer relation to the liquid being supplied to the boiler.

In the accompanying drawings, wherein I 50 have illustrated one typical installation of the improved fluid feed device:

Fig. 1 is a more or less diagrammatic view of a refrigerating system in which my boiler feed device is employed; and

Fig. 2 is a central section through the boiler which forms part of the apparatus shown in Fig. 1.

For purposes of convenient illustration I have shown my improved fluid pumping or 60 feeding means employed in conjunction with the boiler of a refrigerating system of the general type disclosed in my copending application referred to above and the copending application of Lyman F. Whitney, Serial No. 65 159,343, filed January 6, 1927, patented June

3, 1930, #1,761,762. It is evident, however, that means of this character may also be employed with comparable advantage for a wide variety of purposes and in widely different installations.

The accompanying drawings illustrate a refrigerating system which may employ a propellant liquid such as a hydrocarbon of the petroleum family, for example, of the character of heavy kerosene or mineral oil, 70 while the refrigerant may be a suitable more volatile liquid such as water. A system of this character comprises a boiler 1 in which the propellant is vaporized and from which it rises through the pipe 3 to the aspirator nozzle 4 where there is a large increase in velocity and decrease in the pressure of the propellant vapor stream. Liquid refrigerant is contained in the cooler 5 and refrigerant vapor is drawn from this liquid through 75 the duct 20, being entrained in the propellant stream which gives up its kinetic energy in the pumping of the refrigerant vapor. The mixture of refrigerant and propellant vapors passes into the inclined funnel 6 80 which is provided with cooling means 21 in order to cause condensation of the major portion of the propellant at a comparatively high temperature and the drainage of the 85 same toward the lower end of the funnel. 90

It is thus evident, for example, that the temperature of the funnel 6 is normally below the condensation point of the mineral oil or other propellant employed and above the condensation point of the water or other refrigerant employed at the pressure conditions prevailing within the system. Accordingly the refrigerant vapor flows upwardly through passage 22 which has a substantially horizontal connection to a duct 23 that is connected to a condenser 7. The refrigerant condenses in the latter and flows downwardly through duct 23 which is provided with a suitable liquid trap 24 connected to the cooler 5. The connection of pipe 22 to duct 23 is so arranged that a column of liquid refrigerant at the bottom of the latter which is sufficient to balance the liquid in the other leg of trap 24 and in the cooler will not overflow into pipe 22 but so that a column formed by the lighter propellant will overflow into that pipe rather than flow through the liquid trap into the cooler. As refrigerant collects in the liquid column within pipe 23 a portion of the same returns to the cooler, thus completing the refrigerant circuit.

A pipe 30 is connected to the lower end of funnel 6 to receive condensed propellant from the same and from the upwardly extending pipe 22. This pipe is arranged to return the condensed propellant to the boiler for recirculation.

In accordance with the present invention, special fluid flow inducing or pumping means is provided to permit the fluid to be pumped

from the pipe 30 at low pressure to the boiler at a higher pressure. Fig. 2 illustrates more in detail the arrangement of this pumping means which comprises a chamber 31 surrounding the boiler and containing a supply of the liquid received from pipe 30. The boiler 1 preferably is provided with a cup-like wall portion 33 which is formed of suitable porous material having a multiplicity of capillary passages to permit liquid flow through the same. The edges of the cup member 33 are pressed by springs 34 against a suitable gasket 35 disposed upon one end 36 of the chamber 31, it thus being evident that this wall of the chamber also cooperates with the cup 1 in forming the boiler.

The heating factor 37 preferably is arranged within the boiler out of direct heat transfer relation to the liquid contained in chamber 31. For this purpose the heating factor preferably is disposed adjoining the wall 36 of the chamber which also forms an end of the boiler. If a heating factor of the combustion type is employed it may be arranged as shown in Fig. 2, wherein the fuel supply nozzle 39 is shown projecting through the wall 36 of the boiler into a suitable combustion chamber 40. The latter is provided with an intermediate baffle 41 separating nozzle 39 from the outlet to the flue 42 through which burned gases are exhausted to the atmosphere, it being evident that the baffle 41 is mounted on the wall 36 and extends for a substantial portion of the width of the firebox, thus causing the hot gases to sweep past all portions of the wall of the combustion chamber.

The material of the porous cup 33 is so chosen in reference to the liquid that is to flow through the capillary passages of the same that that liquid will readily wet the surfaces of the passages and also have a small and preferably a substantially infinitely small angle of contact with these surfaces.

Furthermore the capillary material is so chosen that its largest pores have a diameter sufficiently small to permit the desired difference between the pressures at opposite sides thereof.

In order to permit the ready conduction of heat from the wall of combustion chamber 40 to the inner surface of the porous cup 33, I partially fill the boiler with a heat conductive material 45 which will be a liquid when the boiler reaches its normal working temperature. Thus, for example, the material 45 may be mercury, lead, type metal; or other material having suitable low melting point and high boiling point may be employed for this purpose. It is further to be understood that this material is so chosen in relation to the material of the porous cup that it will not wet the walls of the capillary passages thereof.

When the material of the porous cup has

thus been properly chosen in relation to the properties of the circulating liquid, the increase of pressure within the boiler due to the evaporation of the liquid at the inner side of the porous cup will merely tend to stretch the concave liquid surfaces at the ends of the capillary passages without substantial change in the position of the edges of the same that contact with the walls of the passages, thus permitting the pressure within the boiler to be substantially higher than that within the pipe 30. When the capillary material and liquid are properly chosen in this manner, evaporation from the liquid surfaces will at once be replenished by additional liquid supplied from the chamber 31 without any tendency of the liquid surfaces at the ends of the capillary tubes to retreat under the pressure differential imposed thereon. Since the surface tension of the liquid alters the pressure relations under these conditions, the heat necessary to cause ready vaporization of the same is slightly greater than that which otherwise would be required. This increase in the energy that is required to effect the vaporization of the fluid is effective in conjunction with the employed capillary means in pumping the fluid against the pressure differential and accordingly the vapor is slightly superheated as it leaves the capillary passages.

It is evident that the magnitude of the pressure differential against which the fluid may be pumped is determined by the surface tension of the circulating liquid and the fineness of the coarsest pores within the porous solid. The structural arrangement illustrated herein permits the maintenance of a substantially fluid-tight seal between the end of the porous cup and the chamber 31 despite changes in the size of these elements due to thermal expansion as long as the joint between the gasket 35, which may be formed, for example, of asbestos, and the cup 1 is no greater than the capillary passage, this joint being effective in permitting the satisfactory operation of the apparatus.

I claim:

1. Fluid feed apparatus of the class described, comprising a fluid duct having a low pressure portion and a high pressure portion, a wall of porous material in the duct providing a multiplicity of capillary passages between the low pressure region and the high pressure region, means for supplying heat to the high pressure region whereby liquid passing through the capillary passages is vaporized, the surface tension of the liquid in the capillary tubes supporting the pressure at the ends of said tubes, and heat conductive liquid in engagement with the porous material at its warm side whereby heat is conducted to the ends of the capillary passages to aid vaporization therefrom, said heat conductive liquid having a higher boiling point

than that of the fluid flowing through the passage.

2. Fluid feed apparatus of the class described, comprising a fluid duct having a low pressure portion and a high pressure portion, a wall of porous material in the duct providing a multiplicity of capillary passages between the low pressure region and the high pressure region, said porous material being of such a character that the liquid will have a substantially infinitely small angle of contact with the walls of the capillary passages, means for supplying heat to the high pressure region, whereby liquid passing through the capillary passages is vaporized, the surface tension of the liquid in the capillary tubes supporting the pressure at the ends of said tubes, and heat conductive liquid in engagement with the porous material at its warm side whereby heat is conducted to the ends of the capillary passages to aid vaporization therefrom, said heat conductive liquid having a higher boiling point than that of the fluid flowing through the passage.
3. Apparatus of the class described comprising a liquid supply passage, a chamber at the end of the passage, a boiler within the chamber, said boiler having a wall formed of porous material providing a plurality of capillary passages adapted to be wet by the liquid from the passage and to have a substantially infinitely small angle of contact with the same, a heating factor disposed out of direct heat transfer relation to the walls of the chamber and in heat transfer relation to the boiler, and a vapor outlet pipe connected to the boiler, said boiler being partially filled with material which is liquid but substantially non-volatile at the normal boiler temperature.
4. Apparatus of the class described comprising a liquid supply passage, a chamber at the end of the passage, a boiler within the chamber, one wall of the boiler being formed by a portion of the chamber wall, the remainder of the boiler having a wall formed of porous material providing a plurality of capillary passages adapted to be wet by the liquid from the passage and to have a substantially infinitely small angle of contact with the same, a heating factor disposed out of direct heat transfer relation to the walls of the chamber and in heat transfer relation to the boiler, and a vapor outlet pipe connected to the boiler, and means yieldably holding the porous boiler wall portion against the wall of the chamber, said vapor pipe and the heat supplying means being connected to said chamber wall.
5. A method of feeding fluid from a region of low pressure to a region of higher pressure and concomitantly evaporating the fluid, which comprises feeding the fluid as a liquid to a wall of capillary material between the two regions, permitting said liquid to

pass into a multiplicity of capillary passages in said material, maintaining a higher temperature at the side of the material toward which the fluid is flowing whereby liquid is evaporated, the pressure being supported by the surface tension of the liquid and maintaining a heat conductive liquid of high boiling point in contact with the warm side of the capillary material to augment evaporation of the liquid.

6. A method of feeding fluid from a region of low pressure to a region of higher pressure and concomitantly evaporating the fluid, which comprises feeding the fluid as a liquid to a wall of capillary material between the two regions, permitting said liquid to pass into a multiplicity of capillary passages with the end of which the liquid makes a substantially infinitely small angle of contact in said material, maintaining a higher temperature at the side of the material toward which the fluid is flowing, whereby liquid is evaporated, the pressure being supported by the surface tension of the liquid, and maintaining a heat conductive liquid of high boiling point in contact with the warm side of the capillary material to augment evaporation of the liquid.

Signed by me at Boston, Massachusetts, this 18th day of July, 1929.
